UNITED STATES PATENT OFFICE.

JOHN B. CLOPTON, OF ELGIN, TEXAS.

MECHANICAL TELEGRAPH-SOUNDER.

SPECIFICATION forming part of Letters Patent No. 229,095, dated June 22, 1880.

Application filed November 14, 1879.

To all whom it may concern:

Be it known that I, JOHN B. CLOPTON, of Elgin, in the county of Bastrop and State of Texas, have invented a new and Improved Mechanical Telegraph-Sounder, of which the following is a specification.

The object of my invention is to furnish an instrument adapted for the use of learners for practicing the manipulation of a telegraph finger-key, and to construct such instrument in a simple and convenient form for sounding without the use of a battery.

My invention consists in a sounder wherein a finger-lever and sounding-lever are combined together with a spring in such manner that the action is very delicate and sensitive and produces a sharp clear sound.

The construction will be described with reference to the accompanying drawings, wherein Figure 1 is a side elevation of the instrument, partially in section. Fig. 2 is a plan view. Fig. 3 is a section showing the manner of pivoting the sounding-lever to the post.

Similar letters of reference indicate corresponding parts.

The instrument is to be made of a size suitable for carrying in the pocket or hand, and adapted for sitting upon a table or other convenient place, and will be mounted on a solid or hollow stand or base, *a*, to increase the sound.

Upon the base *a*, near one end, is attached an arm or post, *b*, of spring-steel, projecting upward, which arm is the fulcrum of the finger-lever *c*. Near the other end of base *a* is fixed a post, *d*, which is the fulcrum of the sounding-lever *e*.

f is a staple fixed in base *a*, against which the lever *e* strikes in its downward movement, and *g* is a screw-plug in the lever *e*, for arresting the upward movement of lever *e*. The lever *e* is provided with a button, *c'*, at its moving end.

The post *d*, as shown most clearly in Fig. 3, is grooved in a vertical direction to receive the end of lever *e*, and grooved or nicked crosswise to receive the knife-edge pivots *1*, that project at each side of lever *e*.

The lever *e* is formed with a slotted lug or

projection, *2*, that sits over the lever *e*, which lug is slotted crosswise to receive the knife-edge pivots *1*, whereby the said pivots *1* and lever *e* are held between the post *d* and lug *2*.

The finger-lever *c* is held to the spring-post *b* by a pointed lug, *3*, on *b* entering the end of *c*, as shown; or it may be attached and held in any other suitable manner whereby the spring-arm *b* will exert its tension to retain the parts in place.

The pivots *1* are arranged so that the bearing on the lug *2* is above the bearing on post *d*; or, in other words, a line drawn through both knife-edges would pass above the pivot *3* of arm *b*, whereby the tension of spring *b* is exerted to raise the moving end of sounding-lever *e*.

To operate the instrument, the knob *c'* will be pressed down, which action throws the outer end of lever *e* in contact with the staple *f*. On release of knob *c'* the spring-fulcrum *b* throws lever *e* up against the screw *g*. By adjustment of screw *g* the length of stroke is regulated.

This construction gives a very sensitive action, while the slight pressure required to move the key is sufficient to produce a sharp sound.

It will be seen that the power of spring *b* diminishes as the finger-lever *c* is pressed down and the knife-edges come nearer to a horizontal plane, so that any pressure sufficient to start the lever downward will carry it down with increasing speed to strike the blow. On return the power of spring *b* increases as the lever rises, so that sufficient force is accumulated for the blow. This peculiar action renders it impossible for the operator to stop the sounding-lever between its contact-points and insures a blow at every movement.

If desired, the post *d* may be the spring and post *b* rigid.

Having thus described my invention, I claim as new and desire to secure by Letters Patent—

1. The mechanical sounder consisting of the finger-lever *c*, hung on post *b*, the sounding-lever *e*, sustained between post *d* and a projection from lever *c*, and the posts *b*, *d*, one of

which acts as a spring, all combined together with a base and suitable contact-points, substantially as described and shown.

2. In mechanical sounders, the combination, with the swinging finger-lever *e*, of the sounding-lever *e*, hung by knife-edges between a fixed post and a projection from lever *e*, the

fixed supports being arranged to impart spring tension, substantially as and for the purposes specified.

JOHN BENJ. CLOPTON.
